[57] **CLAIM**

The ornamental design for unit shelving, as shown and described.

DESCRIPTION

FIG. 1 is a front, quartering perspective view of unit shelving showing my new design;

FIG. 2 is an end elevation of the design of FIG. 1; the opposite end elevation is a mirror image of that shown in FIG. 2;

FIG. 3 is a front elevation of the design of FIG. 1; the rear elevation is a mirror image of that shown in FIG. 3;

FIG. 4 is a top plan view of the design of FIG. 1;

FIG. 5 is a bottom view of the design of FIG. 1;

FIG. 6 is a front, quartering perspective view of an alternate embodiment of unit shelving showing my new design;

FIG. 7 is an end elevation of the design of FIG. 6; the opposite end elevation is a mirror image of that shown in FIG. 7;

FIG. 8 is a front elevation of the design of FIG. 6; the rear elevation is a mirror image of that shown in FIG. 6;

FIG. 9 is a top plan view of the design of FIG. 6; and,

FIG. 10 is a bottom view of the design of FIG. 6.
